UNITED STATES PATENT OFFICE.

JAMES J. FISHER, OF TOWNSEND, MONTANA.

AUTOMOBILE-PULLER.

1,091,318.

Specification of Letters Patent. Patented Mar. 24, 1914.

Application filed September 27, 1912. Serial No. 722,726.

To all whom it may concern:

Be it known that I, JAMES J. FISHER, a citizen of the United States, residing at Townsend, in the county of Broadwater, 5 State of Montana, have invented new and useful Improvements in Automobile-Pullers, of which the following is a specification.

This invention relates to automobile pullers, the object in view being to provide a simple, strong and reliable, portable pulling device for removing automobiles from ditches, or muddy places in which they may become embedded, the device as a whole being sectional and of knock-down construction, so 10 that the parts thereof may be compactly stored in and carried by the machine, in connection with which the same is to be used in an emergency.

With the above and other objects in view, 20 the invention consists in the construction, combination and arrangement of parts, as will be hereinafter more fully described, illustrated in the accompanying drawings, and pointed out in the claim hereunto appended.

In the drawings: Figure 1 is a side elevation, showing the manner of utilizing the puller. Fig. 2 is a plan view on an enlarged scale omitting the spikes. Fig. 3 is 30 an end elevation, partly in section, showing the brace joint. Fig. 4 is a detail perspective view of one of the side members. Fig. 5 is a reverse perspective view of one of the braces. Fig. 6 is a perspective view of the 35 hand lever and its extension. Fig. 7 is a perspective view of one of the spikes.

The puller contemplated in this invention comprises the two main longitudinal bed pieces 1, each comprising a bottom 2, and 40 an upstanding bearing flange 3 extending longitudinally thereof and provided with a hole 4 for the reception of the shaft of the winding drum, hereinafter referred to. Each of the bed pieces is also provided at 45 its opposite ends with a tubular portion or extension 5 provided in the top and bottom thereof with slots 6 for the reception of anchoring spikes, each of said slots being provided with a central offset 7 adapted 50 to receive a corresponding flange on the spike. It will also be noted that the upper slots are offset out of vertical alinement with the lower slots, so that when the spikes are driven into the ground, said spikes will 55 stand at an angle, thereby obtaining a better hold upon the ground. Each of the

spikes comprises a flat or broad main body 8, and is provided along the back thereof with a longitudinally extending reinforcing rib 9, the slots in the bed pieces being correspondingly shaped to receive the spikes, as 60 hereinabove described.

The two bed pieces which stand in a substantially parallel relation to each other when set up are connected at or near their 65 opposite ends by cross braces 10, each of which is formed of sheet metal bent to form the longitudinal flanges 11, and end flanges 12, which are provided with notches 13 adapted to fit detachably over headed studs 70 14 at the inner sides of the tubular extensions of the side bed pieces. This enables the bed pieces to be firmly connected together and braced, and at the same time the form of connection described enables the 75 bed pieces and the braces to be detached or separated, in order to compactly store the same in the automobile.

15 designates a winding drum, upon which a cable 16 is wound, said drum being provided with the end guard flanges 17. The shaft 18 of the drum is journaled at its opposite ends in the bearing flanges of the bed pieces, and adjacent to one end the drum is provided with ratchet teeth 18' adapted 80 to be engaged by a pawl 19, pivotally connected, at 20, to a hand lever 21 having at one end of a hole 22, adapting it to fit over one end of the shaft of the drum, so that it may be subsequently removed therefrom, 90 for compact storage. The lever is substantially V-shaped in cross section adjacent to its outer end, and is provided with headed studs 22' extending upward from the opposite sides thereof and adapted to be engaged 95 by notches 23 in the inner end of a correspondingly shaped extension lever 24. The connection between the two lever sections enables them to be separated, so that they may both be readily stored under the seat 100 of an automobile.

25 designates a detent pivotally mounted on one of the bed pieces and adapted to engage the ratchet teeth on the drum, so as to prevent the backward movement of said 105 drum, during the operation of the device.

It will be understood that the pulling device as a whole is of sectional construction, and made up of a number of parts, all of which may be readily detached from each 110 other for storage and transportation. The device as a whole may be readily carried in

the automobile and may be quickly set up when needed, sufficient power being obtained therefrom to draw any ordinary automobile or truck out of a mud hole, ditch, or the like. By arranging the slots in the upper and lower portions of the tubular extensions out of vertical alinement with each other, the spikes are held sufficiently away from the vertical to obtain a thorough and efficient anchorage and hold in the ground, whether the latter be hard or soft, avoiding the tendency of the device as a whole to pull itself out of place when stress is brought to bear thereon.

15 What is claimed is:

A portable knock down puller for motor driven vehicles comprising two main longitudinal bed pieces each embodying a base wall and parallel upstanding flanges along

the edges of said base wall, a hollow upstanding head at each end of said bed piece having spike receiving holes in the top and bottom wall thereof which holes are out of vertical alinement with each other, central longitudinal upstanding bearing webs on 25 said bed pieces parallel to and interposed between said flanges, cross braces having a detachable connection at their extremities with the bed pieces, a winding drum journaled in said bearing webs and detachable 30 therefrom, and detachable ratchet lever mechanism for operating said drum.

In testimony whereof I affix my signature in presence of two witnesses.

JAMES J. FISHER.
